SPRAY NOZZLE

Herman L. Rowell, United States Army

Application March 31, 1944, Serial No. 528,914

2 Claims. (Cl. 299—120)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to a type of spray nozzle particularly useful for extinguishing fires of materials such as magnesium bombs and liquid fuels which burn stubbornly at high temperatures.

Numerous spray nozzles are known to have been developed for fire fighting and other applications, and many of these have been perfected for particular purposes. Yet, when the problem of quickly extinguishing burning magnesium bombs seriously arose, it was difficult to find any effective spray nozzle for this purpose.

Nozzles which do not fully atomize a stream of water but emit a jet of water in the midst of a fine spray are not suitable because the jet will make a burning magnesium incendiary react with explosive violence. On the other hand, nozzles known to be designed for complete atomization have had various drawbacks in being expensively constructed, large, requiring inflowing feed streams of very high velocity, having small orifices which become clogged, and in forming hollow sprays difficult to focus and concentrate on a burning incendiary.

An object of the present invention is to provide a spray nozzle which avoids the drawbacks noted and which has a simplified construction so it can be made economically by mass production for wide distribution and use.

In general, the nozzle of the present invention has a conical-shaped body tapering from an upstream inlet to a downstream outlet or discharge orifice and includes within the body a means for separating an axially flowing solid stream of liquid into a plurality of spiral streams changed in velocity and forced to impinge on converging inner walls of the nozzle so that the liquid becomes fully atomized with low resistance. The nozzle is adapted for attachment to pipe or hose installations of various sizes and supplying liquid under various pressure and velocity heads.

The fog-producing or atomizing action of the nozzle is mainly dependent upon the shape of the structure within the nozzle and its relationship to inner walls of the nozzle body converging toward an outlet orifice.

Preferably, the inner structure comprises a solid plug tapered toward the inlet and centrally disposed near the inlet of the nozzle with a series of curved vanes or blades adjoined. The blades are disposed to divide the solid stream from the inlet into a plurality of spiral streams curved toward

the inner wall of the nozzle converging toward the outlet orifice of the nozzle. Each blade has a concave surface which is nearly parallel for a substantial portion to a plane along the longitudinal axis of the nozzle beginning at the upstream edge of the blade, then curves more toward the upstream direction. The blades have a gradually increased thickness from both end tips or edges toward the center. The reverse side of each blade is convex and faces toward a concave surface of an adjacent or neighboring blade.

At the discharge end of the nozzle, it is preferred to have an orifice outlined by the thin edge of an inward projection triangular in cross-section.

A spiral stream of liquid flowing between two of the fixed blades is given an increased velocity by contraction in cross section and is diverted at a suitable angle from the axis of the nozzle toward the nozzle wall for impingement and deflection toward the orifice, thus avoiding excessive resistance.

The principles of the nozzle will be explained in more detail with reference to the drawing 25 which illustrates a practical embodiment of the type of nozzle suited for extinguishing magnesium incendiary fires.

In the drawing:

Figure 1 is a sectioned, longitudinal side view of 30 the nozzle body and holder assembly with a side full view of means within the nozzle for separating a solid stream of liquid entering the nozzle into a plurality of curved streams;

Figure 2 is a sectional view of the nozzle body 35 along the longitudinal axis of the nozzle;

Figure 3 is a perspective side view of the tapered plug and blade means; and

Figure 4 is a cross-section view taken along the line A—A in Figure 1 and in the direction of the 40 arrows.

Referring to the drawing, and in particular to Figure 1, the holder comprises a tubular body 1 threaded internally at the inlet end 2 and externally at the outlet end 3. Gaskets 4 are seated 45 against a retaining ring 5 within the body 1 adjacent to the internal thread 2 for making a tight connection with a hose coupling. The external threaded outlet end 3 is tapered beginning at a flange 6.

Referring particularly to Figure 1, nozzle body 7 has an internally threaded flange 8 for engaging the externally threaded end 3 of the nozzle holder and a recessed gasket seat 9 for holding gasket 10. The exterior walls of the nozzle body 7 may be tapered conically from the flange 8 toward the

discharge end 11, but internally for a portion of the distance beginning at the inlet, the walls may be substantially cylindrical, as, for example, up to a point 12, and thence be tapered to form an angle of about 15 to 25° with the longitudinal axis of the nozzle as they converge to the outlet orifice 13.

Close to the discharge end of the nozzle the gradual converging or arching of the inner wall, preferably ogival in contour, abruptly ends; and at this point, or slightly beyond, the inner wall slants sharply toward the longitudinal axis, making an angle of close to 70° therewith and ending in the sharp tip 13, triangular in cross-section. The thin edge of this sharp tip is the perimeter of the outlet orifice. It defines the shape of the issuing mist stream. The orifice piece having the tip 13 may be in the form of a replaceable insert secured to the discharge end of the nozzle or integral therewith. This piece may have a cylindrical surface section which meets the end of the ogival surface and leads to the tip 13.

The structure shown in Figure 3 is the means inserted within the nozzle close to the inlet for separating the entering solid stream of liquid into a plurality of curved streams. It is set into the nozzle as shown in Figure 4 with the tapered solid plug 14 centrally disposed and with the adjoining curved vanes or blades 15 extending from the plug to the surrounding inner wall of the nozzle. Four of these blades make a suitable number; and with four blades, each blade is radially positioned at 90° from an adjacent blade. The blades are identically shaped with a concave surface 16 beginning at the upstream edge approximately parallel to a plane through the longitudinal axis of the nozzle and then curving at a suitable angle toward a side of the nozzle and with a convex surface 17 facing and converging with the concave surface of an adjacent blade. It is also preferred to have the cross section of the blades gradually increase from both edges toward the centers.

With the blades thus shaped and positioned, a stream of liquid entering the nozzle is divided into four separate spiral streams, and each of these separate spiral streams first flows axially between a pair of adjacent blades, then becomes curved and constricted in the narrowed passageway between a concave surface and a convex surface near the downstream ends of adjacent blades.

The center structure of plug and blades, conveniently made by casting as one piece, is readily inserted into the nozzle through the inlet opening, and may be fixed in place by a set screw fastened into the depression 18 of a blade through threaded opening 19 in the nozzle wall and by soldering.

The curved spray streams, on leaving the blades, are diverted from the axis preferably by about 55 to 85° and then impinge upon the tapered inner wall of the nozzle which makes an angle of about 15 to 25° with the longitudinal axis. By making this angle of impingement, the streams at increased velocity, leaving the spaces between the blades, impinge forwardly upon the inner walls to become broken up into fine droplets which then are directed out through the orifice on rebounding. The mass of droplets ejected from the orifice is substantially homogeneous and bulb-like in form.

Spray nozzles of the type illustrated were made for fitting average small-size hoses, such as might be found installed commonly in buildings with

about 1 1/4 inch inside diameter and ordinary water pressures, and were found to perform satisfactorily. They were also used in successful air-raid defense demonstrations of exemplary methods for extinguishing magnesium incendiary bombs. It is considered that they are very effective for this purpose by virtue of the localized high-cooling action by the quickly vaporizing fog they lay down surrounding a bomb.

An advantageous feature of the described nozzle is that the divided liquid at all times has a substantially forward moving vector so that at no place is the flow completely obstructed. Another feature resides in the shaping and positioning of the blades to impart increased velocity at the place in the nozzle where the impingement is to effect the atomization. With spiralling, relatively high velocity, the liquid is subjected to several atomizing forces simultaneously, such as a centrifugal force, an impact force, and a forward velocity force.

With high efficiency for completely atomizing a stream of liquid, spray nozzles embodying the features of this invention are adapted to many uses, as, for example, for precipitating dust, air washing, cooling ponds, humidifying air, spraying liquids in condensers, atomizing liquids in vaporizers, reactors, dryers, absorbers, and the like. The nozzles may be varied in size to suit the needs.

While, for the sake of simplicity, one type of nozzle has been illustrated, it is to be understood that modifications may be made which come within the spirit of the invention.

I claim:

1. A spray nozzle for ejecting a homogeneous mass of liquid droplets comprising a tubular conduit converging for at least a portion of its length from an inlet to an outlet, a centrally spaced solid plug tapered toward the inlet and spaced from inner surfaces of said conduit, a series of blades disposed around said plug said blades having concave curved surfaces and convex curved surfaces, each of said blades having a gradually increased thickness from the end tips toward their centers, and the distance separating the concave surface of one blade from the convex surface of an adjacent blade becoming gradually smaller in a downstream direction.

2. In a spray nozzle for fully atomizing a solid stream of liquid, a set of radially spaced curved blades, each blade having a relatively wide edge pointing substantially into an entering solid stream of liquid and a relatively narrow edge pointing downstream toward impingement wall surfaces in said nozzle, and each blade having gradually increased thickness from both said edges toward the center of the blade.
